(57) **CLAIM**

The ornamental design for a tire tread, as shown and described.

DESCRIPTION

FIG. 1 is a perspective view of a tire including a first embodiment of a tire tread of the present application taken generally from the front and a first side of the tire;

FIG. 2 is a front view of the embodiment of FIG. 1, and any top, bottom, or rear view thereof would be the same as the front view;

FIG. 3 is a side view of the first side of the embodiment of FIG. 1, second side view being the same as the first side view;

FIG. 4 is an enlarged, partial perspective view of the embodiment of FIG. 1 taken generally from the front and first side of the tire;

FIG. 5 is an enlarged, partial front view of the embodiment of FIG. 1; and,

FIG. 6 is an enlarged, partial side view of the first side of the embodiment of FIG. 1.

The broken lines depict subject matter that form no part of the various embodiments of the claimed tire tread designs, and are included for the purpose of illustrating the full tire, and the annular region between the broken lines defining the inner beads and the shoulder where the outer edges of the tire joins the sidewall forms no part of the claim. Likewise, the tire interior forms no part of the claim. The tread pattern is understood to repeat throughout the circumference of the tire.

1 Claim, 6 Drawing Sheets
